Primary Examiner — Robert M Spear*Assistant Examiner* — Darcey E Heflin(74) *Attorney, Agent, or Firm* — Flynn, Thiel, Boutell & Tanis, P.C.(57) **CLAIM**

The ornamental design for a dispenser head, as shown and described.

DESCRIPTION

FIG. 1 is a perspective view of a dispenser head showing my new design;

FIG. 2 is a front view thereof, with the rear view being a mirror image thereof;

FIG. 3 is a right side view thereof, with the left side view being a mirror image thereof;

FIG. 4 is a top view thereof; and,

FIG. 5 is a bottom view thereof.

The broken lines illustrating portions of the dispenser head are for environmental purposes only and form no part of the claimed design.
